UNITED STATES PATENT OFFICE

JAMES HENRY FLOOD AND HENRY FREDERIC KNOEDER, OF CARDINGTON,
OHIO.

CAR-COUPING.

SPECIFICATION forming part of Letters Patent No. 288,789, dated November 20, 1883.

Application filed March 3, 1883. (No model.)

To all whom it may concern:

Be it known that we, JAMES H. FLOOD and HENRY F. KNOEDER, both of Cardington, in the county of Morrow and State of Ohio, have 5 invented a new and Improved Car-Coupling, of which the following is a full, clear, and exact description.

Our invention consists, principally, of certain attachments to be used with specially-formed draw-heads or with draw-heads in common use, whereby the ordinary link-and-pin car-couplings may be made automatic in coupling cars.

The invention also consists of a clasp-rod for 15 raising the coupling-pin from the top or sides of the car for uncoupling the cars, which rod is also provided with a set-screw for limiting the upward movement of the rod, to prevent the coupling-pin being raised too high or entirely out of the draw-head.

Reference is to be had to the accompanying drawings, forming part of this specification, in which similar letters of reference indicate corresponding parts in all the figures.

25 Figure 1 is a sectional elevation, showing our coupling attachment applied to draw-heads made especially to receive them, and showing the parts in the position they assume just before coupling. Fig. 2 is a plan view of 30 the same, one of the draw-heads being in section. Fig. 3 is a front elevation of one of the draw-heads and coupling attachment. Figs. 4 and 5 show a separate rod for lifting the guide-plate; and Fig. 6 is a sectional elevation, showing our invention applied to an ordinary draw-head.

35 A is a guide-plate for guiding the connecting-link E into the throat of the draw-head B. This plate is preferably slightly concaved, and 40 is pivoted between the members a a of the divided sliding bar C, which is held in the draw-head by the pin b, that passes through the draw-head and through the slot d in the bar. In front of the pin b is placed, in the slot d, the 45 spring f, which serves, when the coupling-pin D is raised, to force the sliding bar C and guide-plate A out of the draw-head to the position shown at the right of Figs. 1 and 2, in which position the outer end of the guide-plate A will drop down so as to stand at an

inclination of about forty-five degrees in front of the lower edge of the draw-head, as shown in said figures.

To prevent the outer end of the guide-plate A dropping down too low, we provide the 55 sliding bar C with the stop-pins c c, against which the rear ends of the arms e e of the guide-plate A are adapted to come, as clearly shown in Figs. 1 and 2.

The sliding bar C, besides being formed with 60 the members a a, is formed with the central projection, g, which stands on a higher level than the members a a, and under which projection the connecting-link E is adapted to 65 strike when the cars are backed together for coupling, so that the sliding bar C will be forced by the impact of the cars back against the pressure of the spring f into the draw-head, and the backward movement will force the guide-plate A within the draw-head, and 70 will be sufficient to cause the sliding bar C to clear the coupling-pin D, thus permitting it to drop through the link, and thus retain it.

The upper surface of the sliding bar is flattened, or, preferably, slightly grooved out, as 75 shown at i, for forming a proper support for the lower end of the coupling-pin D, for holding the pin in an elevated position when the connecting-link E is not in place in the draw-head, and so that there will be no danger of 80 binding or uncertain action of the pin when the link enters the draw-head.

When our invention is to be used with specially-made draw-heads, the sliding bar C will 85 be made of considerable length, and the draw-heads will be chambered out back a sufficient distance to receive them; but when applied to draw-heads already in use, the length and form of the sliding bar will be made to conform to the size and shape of the throat of the 90 particular form of draw-head, as will be understood from Fig. 6, and in most cases it will be found necessary to support the outer end of the sliding bar C upon the separate metal block F, secured in the draw-head by bolts or 95 rivets, as will be understood from said Fig. 6.

To the outer end of the central projection, g, is pivoted the weighted dog G, which is adapted for holding the coupling-pin in an elevated position, as illustrated in Fig. 4. The 100

weighted dog G is scarf-jointed, and its upper and lower portions are pivoted together at t, so that the lower portion will be rigid when the link strikes it to trip the pin, in coupling 5 the cars, and to permit free withdrawal of the link—should part j fall within the link in uncoupling—said part j is free to swing outward with the link, while the part j' remains in position to support the coupling-pin, as 10 will readily be understood. In draw-heads already in use, this dog G may be pivoted in the throat of the draw-head, as shown in Fig. 6, so that when the coupling-pin D is raised, the rear end, j, of the dog G, which is of sufficient 15 weight to counterbalance the weight of the pin, will drop down, bringing the forward part, j', of the dog under the pin, thus supporting it until the entrance of the connecting-link E in the draw-head strikes the lower 20 and heavier part, j, which will trip the dog and let the coupling-pin D drop.

In case it is not desired to depend wholly upon the spring f for forcing the sliding bar C and guide-plate A out of the draw-head, we 25 may form the guide-plate with the central lip or projection, a', against which the connecting-link E will strike in being drawn out of the draw-head in uncoupling, thus drawing the sliding bar and guide-plate out with a positive 30 action; and in order to tip the outer end of the guide-plate A upward, for entering the connecting-link into the draw-head before the link strikes the sliding bar C under the central projection, g, we may provide one member a of the sliding bar C with the protruding push-rod H, and the guide-plate A with the upwardly-projecting lip h', against which the inner end of the rod H is adapted to impinge, as shown in Figs. 4 and 5, so that when 35 the opposing draw-head or bar C strikes the outer end, h, of the rod H, to move it inward, it will raise the outer end of the guide-plate A just at the proper time to lift the connecting-link, and always cause it to properly enter 40 the draw-head.

L is the clasp-bar for raising the coupling-pin for uncoupling the cars. This bar L is made in two parts, l l, that are journaled in suitable plates and reach to the sides of the 50 car, and these parts are formed with the corresponding arms, l' l', that are adapted to clasp the coupling-pin, as shown in Fig. 2, and to be drawn together snugly around or against the pin D on opposite sides by the thumb-screw m, as will be clearly understood from 55 said Fig. 2, and to this thumb-screw is attached the small chain P, that leads to the top of the car, so that the cars may be uncoupled by means of this chain from the top of the car, or 60 from the sides of the car by means of the rods l l.

To prevent the rods l l being turned too far in the act of uncoupling, we provide one of them with the short arm o, in which is fitted the set-screw q, which is adapted to come against the 65 car body or platform, as shown in Figs. 1 and 2, and by adjusting this set-screw the coupling-pin D may always be raised just the proper

height, and by it all danger of raising the pin entirely out of the draw-head is obviated.

In use the connecting-link E will be placed 70 in one of the draw-heads of the cars to be coupled, as shown at the left in Fig. 1, and the coupling-pin D of the opposing car will be raised, as shown at the right in Fig. 1, which will permit the sliding bar b and guide-plate 75 A to be forced out of the draw-head by the spring f, so that when the cars are backed together the guide-plate will guide the connecting-link into the throat of the draw-head and against the sliding bar C, which will thus be 80 forced back into the draw-head and from under the coupling-pin D, which pin will then drop through the connecting-link and effect the coupling. In uncoupling it is only necessary to raise one of the coupling-pins, whereupon 85 the weighted dog G will drop to position and support the pin until the link is drawn out of the draw-head, when the sliding bar C will be forced out of the draw-head by the spring f, and the coupling-pin D will then be 90 supported upon the sliding bar C, as shown at the right in Fig. 1. In this manner it will be seen that the coupling is perfectly automatic, is cheap, adapted to be attached to all forms of draw-heads, and is very easily operated, 95 and is certain and reliable in its action.

Instead of using the horizontal pin b for holding the sliding bar C in the draw-head, a vertically-placed headed pin might be used, entering the draw-head at the bottom, and the head of the pin running in a suitable groove made in the under side of the sliding bar. When this arrangement is employed, the vertical pin may serve at the same time to hold the block F in place in the draw-head. 105

Having thus described our invention, what we claim as new, and desire to secure by Letters Patent, is—

1. In a car-coupling, the bar C, arranged to rest in the throat of the draw-head, and mechanism to slide horizontally forward said bar, substantially as set forth, and slide it backward by the impact of two cars, and the guide-plate A, pivoted to the bar C and provided with a stop, substantially as shown and described. 110

2. In a car-coupling, the sliding bar C, formed with the slot d, and held in the draw-head by the pin b, in combination with the spring f and pivoted guide-plate A, substantially as and for the purpose set forth. 120

3. The sliding bar C, having the guide-plate A pivoted thereto, and having the central projection, g, under which the connecting-link is adapted to strike, for forcing the bar 125 and the guide-plate back into the draw-head, substantially as and for the purposes set forth.

4. The sliding bar C, adapted to support the coupling-pin D, and to be forced out of the draw-head by the spring f, the bar being 130 provided with the guide-plate A, substantially as and for the purposes set forth.

5. The combination, with the sliding bar C, having the guide-plate A, of the pivoted,

weighted, and jointed dog G, for supporting the coupling-pin, substantially as and for the purposes set forth.

6. The guide-plate A, provided with the 5 lip or projection a' , substantially as and for the purposes set forth.

7. The clasp-bar L, composed of the rods $l l$, having arms $l' l'$, that surround the coupling-pin, and are drawn together by the thumb-screw w , substantially as and for the purposes set forth.

8. The clasp-bar L, provided with the arm o, having set-screw q , for limiting the distance of movement of the rod, as and for the purposes set forth.
